(57) **CLAIM**

The ornamental design for a fan blade cover, as shown and described.

DESCRIPTION

FIG. 1 is a perspective view of a fan blade cover showing my new design;

FIG. 2 is a front view of the fan blade cover of FIG. 1;

FIG. 3 is a rear view of the fan blade cover of FIG. 1;

FIG. 4 is a left side view of the fan blade cover of FIG. 1;

FIG. 5 is a right side view of the fan blade cover of FIG. 1;

FIG. 6 is a top view of the fan blade cover of FIG. 1;

FIG. 7 is a bottom view of the fan blade cover of FIG. 1; and,

FIG. 8 is an environmental front view of five (5) of the fan

blade covers of FIG. 1 attached to a typical ceiling fan.

Portions of the figures shown in broken lines depict environmental subject matter only and do not form part of the claimed design.

1 Claim, 5 Drawing Sheets
